INVENTOR.

BY

Lawrence Bryant & Darby
ATTORNEY.

UNITED STATES PATENT OFFICE.

WILLIAM E. TURNER, OF TACOMA, WASHINGTON.

SEWING MACHINE.

1,426,617.

Specification of Letters Patent. Patented Aug. 22, 1922.

Application filed April 18, 1921. Serial No. 462,182.

To all whom it may concern:

Be it known that WILLIAM E. TURNER, a citizen of the United States, residing at Tacoma, in the county of Pierce and State of Washington, has invented new and useful Improvements in Sewing Machines, of which the following is a specification.

The present invention relates to improvements in needle plates intended primarily, 10 though not exclusively, for use on machines for stitching soles of shoes.

It is well known in the art to provide a needle plate having thereon a removable cutter whereby the machine may be used for 15 stitching rubber soles in which no channel is to be cut, by simply removing the cutter. This invention relates more particularly to the means for holding the needle plate in position upon the needle plate cap and also 20 to the means for fixedly holding the cutter in position upon the needle plate.

An object of this invention is to provide an extremely simple and efficient means for locking the needle plate upon the needle 25 plate cap and for locking the cutter in position upon the needle plate.

A further object of the invention is to simplify the needle plate construction, thereby cheapening the cost of production of the 30 needle plate, and to provide a single means which will simultaneously serve both to hold the needle plate in position upon the cap and to lock the cutter against movement relatively to the needle plate.

35 The above are the principal objects of the invention, and they, as well as other objects of a more minute character, will become obvious as this description proceeds.

In order that the invention may be clear, 40 there is illustrated in the accompanying drawings one embodiment of the invention, and in these drawings:

Figure 1 is a plan view of the needle plate cap showing the needle plate applied thereto.

45 Figures 2 and 3 are cross sectional views on the lines 2-2 and 3-3 respectively, of Figure 1.

Figure 4 is a perspective of the needle plate, and

50 Figure 5 is a perspective of the cutter removed from the needle plate.

Referring to the accompanying drawings for a more detailed description, 10 indicates a needle plate cap which may be secured to a machine in any suitable manner, as by the usual laterally extending ears 11. At the

forward end of the cap is positioned a needle plate 12 formed of a substantially rectangular flat piece of metal having therein a needle slot 13. The needle plate is fitted 60 within a guide way 14 formed on the needle plate cap and is slidable longitudinally in the guide way in which it is held against all movement, except a sliding movement, by means of the undercut side walls 14' of 65 the guide way which cooperate with the beveled lateral edges 15 of the needle plate to form a dovetail joint.

In order to lock the needle plate against sliding movement longitudinally of the guide 70 way, a U-shaped slot 16 may be formed in the needle plate so as to extend inwardly thereof from its rear end. A screw 17 may be set into the needle plate cap on a line with the slot so that when the needle plate is 75 positioned within the guide way, the screw is in the slot. As will be observed from an inspection of Fig. 4, the needle plate around the edges of the slot is countersunk so that when the screw 17 is tightened against the 80 needle plate to clamp the latter in position, the screw head will be within the countersink.

The needle plate has thereon a removable cutter 18 formed with a base 19 having beveled side edges 20. The base of the cutter fits within a groove or guide way 21 extending from a lateral edge of the needle plate slightly into the needle plate. The groove is formed with undercut side walls 22 for 90 the purpose of forming a dovetail joint with the side walls of the cutter base 19. It will be evident that by reason of this locking joint between the cutter and its shank receiving groove, the cutter will be held against 95 all movement, except withdrawal from the groove. However, when the needle plate is moved into the position shown in Fig. 1 within its guide way, the side wall of the guide way serves not only to hold the needle 100 plate in position, but also serves to lock the cutter in position against withdrawal from its seat.

Obviously, in order to move or dislodge the cutter, it is necessary to withdraw the 105 needle plate at least partially from its guide way, the guide way thereby serving the dual function of locking both the needle plate and the cutter in position.

It will be clear to one skilled in the art 110 that numerous modifications might be made in the described and illustrated embodiment

of my invention while still retaining its essential features which are more clearly defined in the following claims.

What is claimed is:

- 5 1. In combination, a needle plate cap, a needle plate on said cap, a removable cutter on said needle plate and a single means serving both to hold said needle plate against movement on said cap and to lock said cutter in position on the needle plate.
- 10 2. In combination, a needle plate cap having a guideway thereon, a needle plate slideable longitudinally of said guideway and a removable cutter on said needle plate, said guideway serving both to hold the needle plate against movement relatively to said cap and the cutter against movement relatively to said needle plate.
- 15 3. In combination, a needle plate cap having a guideway therein, a needle plate slideable longitudinally of said guideway, said needle plate having a groove closed at one end by a wall of said guideway, and a removable cutter in said groove, said cutter being removable only when the needle plate is withdrawn at least partially from the guideway.
- 20 4. In combination, a needle plate cap having a guideway thereon, a needle plate slideable longitudinally of said guideway and a removable cutter on said needle plate, said guideway serving both to hold the needle plate against movement relatively to said cap and the cutter against movement relatively to said needle plate.
- 25
- 30

atively to said needle plate, said cutter being removable only when the needle plate is at least partially withdrawn from the guideway.

5. In combination, a needle plate cap having a guideway thereon, a needle plate slideable longitudinally of the guideway and dovetailed therein, said needle plate having a groove therein open at one end, said open end being at an edge of the plate meeting the guideway wall, a removable cutter in said needle plate having a shank making a dovetail joint with said groove, said guideway serving both to hold the needle plate in position on the cap and to hold said cutter in position on said needle plate.

40 6. In combination, a needle plate cap having a guideway thereon, a needle plate slideable longitudinally of the guideway and dovetailed therein, said needle plate having a groove therein open at one end, said open end being at an edge of the plate meeting the guideway wall, a removable cutter in said needle plate having a shank making a dovetail joint with said groove, said guideway serving both to hold the needle plate in 45 position on the cap and to hold said cutter in position on said needle plate, the cutter being removable only when the needle plate is at least partially withdrawn from the guideway.

45 50 55 60 65 In testimony whereof I have hereunto set my hand.

WILLIAM E. TURNER,
